INVENTOR

JAMES E. MERWIN

By C. J. Blake ATTY.

UNITED STATES PATENT OFFICE.

JAMES E. MERWIN, OF PORTLAND, OREGON, ASSIGNEE TO A. E. PERRY, OF PORTLAND, OREGON.

SHIM.

1,296,418.

Specification of Letters Patent.

Patented Mar. 4, 1919.

Application filed October 15, 1917. Serial No. 196,768.

To all whom it may concern:

Be it known that I, JAMES E. MERWIN, a citizen of the United States, residing at Portland, county of Multnomah, State of Oregon, have invented certain new and useful Improvements in Shims, of which the following is a specification.

My invention relates to shims in general and particularly to shims adapted for use in tightening such rims of vehicle wheels as are held in place upon the felly by means of bolted lugs.

The object of my invention is to provide convenient, cheap and secure means of shimming up such wheel rims and making them tight upon the wheel.

My invention applies especially to automobile wheels of the removable rim type, and is so illustrated in the accompanying drawing, which forms a part of this application for Letters Patent, like characters of reference indicating like parts throughout the several views, and in which:

Figure 1 is a sectional view of a wheel rim and felly showing my device in use as a single shim.

Fig. 2 is a sectional view of a rim and felly showing my device in use as a double shim.

Fig. 3 is a sectional view of a rim and felly showing my device in use as a triple shim.

Fig. 4 is a perspective view of my device detached, as a single shim, and showing in dotted lines the form of the double shim.

Fig. 5 is a perspective view of my device detached, and shown as a triple shim.

In general my device is designed to be placed between the clip 10 and the felly 11, as shown in Fig. 1, or between the clip and both the felly and the rim 12, as shown in Figs. 2 and 3.

It is formed of a thin sheet of metal, or other suitable material, having an apron 6 bent substantially normal to the body portion 7, said apron having an orifice 8 therein to receive the clip bolt 9.

By suitably slotting the body portion 7 a tongue 13 is formed therein.

A single thickness of material may be inserted as a shim by allowing the body portion 7 to extend across the felly, as shown in Fig. 1.

A double thickness of material may be in-

troduced as a shim by bending the body portion 7 back over the clip 10, as shown in Fig. 2.

A triple thickness of material may be introduced as a shim by further bending the tongue 13 over upon body portion 7 after the latter has been bent back over the clip 10, as shown in Fig. 3.

Thus I am enabled to provide a one piece adjustable shim, several thicknesses of which may be used as necessitated by circumstances.

My invention may be made of any size, and constructed of any material deemed convenient and suitable for a device of this character, and while I have illustrated and described a form of construction found desirable in materializing my invention, I wish to include in this application for Letters Patent all mechanical equivalents and substitutes that may fairly be considered to come within the scope and purview of my invention as defined in the appended claims.

Having disclosed my invention so that others skilled in the art may be enabled to construct and to use the same, what I claim as new, and desire to secure by Letters Patent is:

1. In a one piece shim, a body portion; an apron substantially normal to said body portion; and a tongue in said body portion, adapted to be bent back thereupon.

2. In a one piece wheel shim, a body portion adapted to lie upon the felly of said wheel; an apron substantially normal to said body portion and adapted to receive a bolt through said felly; and a tongue in said body portion, adapted to be bent back thereupon.

3. In an automobile wheel, a felly, a rim, and a plurality of clips; in combination with a plurality of one piece shims embodying means whereby one, two or three thicknesses of said shim may be inserted between said rim and said felly.

4. In an automobile wheel, a rim, a felly, a plurality of one piece clips, and clip bolts; in combination with a plurality of shims each having a body portion adapted to be inserted between said clip and said felly; a perforated apron substantially normal to said body portion and adapted to receive said bolt; an extension upon said body por-

tion adapted to be bent over upon said clip between the latter and said rim; and a member integral with said shim adapted to be bent over upon said extension between the 5 latter and said rim.

In witness whereof I claim the foregoing as my own I hereunto affix my signature in

the presence of two subscribing witnesses, at Portland, county of Multnomah, State of Oregon, this 1st day of October, 1917.

JAMES E. MERWIN.

Witnesses:

C. F. BLAKE,
L. J. ROBINSON.
